PORTABLE SANDER TOOL

Magnus H. Wickman, Minneapolis, Minn.

Application July 14, 1950, Serial No. 173,707

7 Claims. (Cl. 51—190)

1

This invention relates to portable grinders and polishers of the rotary type which are adapted particularly for polishing articles of wood.

Heretofore, all of the portable grinding and polishing tools were incapable of being held in the proper grinding or polishing position with respect to surface being polished, etc. It is necessary during the grinding or polishing operation to exert uniform pressure on the tool so that rapid and proper polishing of the surface is accomplished. I have devised a simple and effective means of holding a grinding tool in the proper grinding position to easily and readily grind or polish a surface in a proper and accurate manner.

One object of my invention is to provide a sander tool which will be operative for quickly and efficiently polishing or grinding any desired surface.

Another object of the invention is to provide a novel handle means on the outer end of a sander tool whereby the tool may be more readily manipulated for efficient operation.

A further object of the invention is to provide in a portable sander or polishing tool a removable abrasive sleeve and means for securely holding the sleeve on a spindle of the tool.

Other objects of the invention, not specifically mentioned hereinbefore, will become apparent during the course of the following description.

In the drawings:

Figure 1 is a side elevational view of the sander tool suitably mounted in the socket of a hand drill and shown in polishing position on a piece of work.

Figure 2 is sectional view taken on line 2—2 of Figure 1, showing the spindle of the tool with the abrasive sleeve thereon.

Figure 3 is an elevational view of the sander tool, parts in section, parts broken away, showing the novel handle of the tool.

Figure 4 is a sectional view taken on line 4—4 of Figure 3 showing the locking or securing means for the removable abrasive sleeve.

Figure 5 is a sectional view taken on line 5—5 of Figure 3, disclosing the bearing means for the handle of the tool and means for maintaining the handle on the shaft of the tool.

Referring specifically to the drawings wherein like reference characters designate like or similar parts, a sander tool is shown generally at 10. A suitable power means 12 such as a portable power driven hand drill is adapted as the means for actuating the sander tool 10. A portion of a shaft of the sander tool is coupled by means of a chuck of the hand drill to the hand drill 12.

The sander tool 10 comprises a metal shaft 14

2

having a wooden spindle 16 appropriately fixedly secured thereto with the ends of the shaft 14 extending beyond the ends of the spindle 16. One end of shaft 14, the right end, see Figures 1 and 3 of the drawings, is adapted to be secured into a chuck of the hand drill 12 whereby the sander tool 10 may be rotated. The left end of the shaft 14, see Figure 3 of the drawings, is provided with a circumferential groove 18. A handle 20 provided with a socket in its inner end and having a metal sleeve 24 carried in the socket 22 is freely mounted on the left end of the shaft 14, see Figures 1 and 3 of the drawings with the metal sleeve 24 acting as a bearing for the end 15 of the shaft 14. A small screw 26 is mounted in aligned holes in the sides of the handle 20 and bearing sleeve 24 with its inner end extending into the circumferential groove 18 of shaft 14 to hold handle 20 on the end 15 of the shaft 14.

The end 17 of the spindle 16 is provided with a circumferentially enlarged portion 19 which is tapered outwardly with respect to axis of the spindle 16. A circumferential recess 21 is formed 25 in the tapered portion 19 of the spindle 16 and two tabs of abrasive material 23 are mounted in the recess 21 each of which is spaced diametrically from the other. A cylindrically shaped sleeve 28 of abrasive material, such as sand paper is removably secured to the outer surface of the spindle 16. The tapered portion 19 of spindle 16 and the abrasive tabs 23 tightly engage the inside of the abrasive sleeve 28 at end 17 of the spindle 16 securely holding the abrasive sleeve 28 on the spindle 16 during the grinding and polishing operations of the sander tool 10.

In the operation of the sander tool 10, the free end of the shaft 14 is securely fastened in the chuck of the power driven hand drill 12. The hand drill 12 with the sander tool 10 mounted thereon is easily and readily portable for use in grinding pieces of metal or articles of wood such as the article of wood 40, see Figures 1 and 2 of the drawings. The user of the sander tool 10 holds the power driven drill device 12 in his right hand with his left hand engaging the handle 20, and the left hand can manipulate and guide the abrading sleeve 28 mounted on the spindle 16 into the proper contact with piece of work 40 for quick and efficient grinding or polishing of the article of wood 40. The drill device 12 will rotate the spindle 16 and its abrading sleeve 28 for grinding or polishing any desired surface such as surface 42 of the wood article 40. The handle 20 provides a convenient means for guiding the tool 10 over the surface being polished and also for giving

it the proper abrasive contact with surface of the work. The metal sleeve 24 in handle 20 provides a convenient and efficient bearing means for the end 15 of shaft 14.

The removable abrasive sleeve 28 is securely held on the surface of spindle 16 under all ordinary operating conditions of the sander tool 10 by means of the tapered portion 19 and its abrasive tabs 23 on the end 17 of the spindle 16. The abrasive sleeve 28 after use in grinding and polishing of surfaces of articles of wood, etc. becomes worn so that a new abrasive sleeve would be needed. So to remove the worn abrasive sleeve 28 from the spindle 16 the end of handle 20 is engaged with a rigid object and then holding the sleeve 28 in the hand and pulling downward on the abrasive sleeve 28 toward the rigid object or surface loosens the sleeve 28 from the tapered surface 19 with its abrasive tabs 23 of the spindle 16 so that worn abrasive sleeve 28 can be removed off the handle end of spindle 16. It will be evident that a new abrasive sleeve 28 can be mounted on the spindle 16 by being pushed over handle 20 onto the spindle 16 until the right end of the new abrasive sleeve 28 tightly engages the tapered portion 19 with its abrasive tabs 23 of the end 17 of spindle 16, see Figure 3 of the drawings.

It is to be understood that the abrasive sleeve 28 can be made of any material such as sandpaper, emery cloth, any grit, or the like.

From the foregoing description taken in connection with the accompanying drawing, it will be readily apparent to those skilled in the art, that this invention provides a simple, but highly practical sander tool which is easily controlled for rapid and efficient grinding and polishing operations.

Various changes may be resorted to, provided they fall within the spirit and scope of the invention as defined by the appended claims.

I claim as my invention:

1. A sander tool of the class described comprising a shaft, a spindle fixedly mounted on the shaft with the ends of the shaft extending beyond the ends of the spindle, a circumferentially outwardly tapered portion with respect to the axis of the spindle formed on one end of the spindle having a circumferential recess formed therein, two abrasive tabs diametrically spaced from each other mounted in the circumferential recess of the tapered portion of the spindle, and an abrasive sleeve mounted on the spindle with the tapered portion of the spindle and its diametrically spaced abrasive tabs normally engaging and holding the abrasive sleeve on the spindle.

2. A portable sander tool of the class described comprising a shaft, a spindle fixedly mounted on the shaft with the ends of the shaft extending beyond the ends of the spindle, a circumferentially outwardly tapered portion with respect to the axis of the spindle formed on one end of the spindle and provided with a circumferential recess, two abrasive tabs spaced diametrically from each other mounted in the recess in the tapered portion of the spindle, an abrasive sleeve mounted on the spindle with the tapered portion and its diametrically spaced abrasive tabs normally engaging and holding the abrasive sleeve on the spindle, and a handle provided with a bearing member freely mounted on the one end of the shaft.

3. A portable sander tool of the class described comprising a shaft, a spindle fixedly mounted on the shaft with the ends of the shaft extending

beyond the ends of the spindle, a circumferentially outwardly tapered portion with respect to the axis of the spindle formed on one end of the spindle provided with a circumferential recess, two abrasive tabs diametrically spaced from each other mounted in the circumferential recess formed in the tapered portion of the spindle, an abrasive sleeve mounted on the spindle with the tapered portion and its diametrically spaced abrasive tabs normally engaging and holding the abrasive sleeve on the spindle, a handle provided with a bearing member freely mounted on the one end of the shaft, and an electric power means adapted to engage the opposite end of the shaft for actuating the tool.

4. A sander tool of the class described comprising a shaft, a spindle fixedly mounted on the shaft, a circumferentially outwardly tapered portion with respect to the axis of the spindle formed on one end of the spindle having a circumferential recess formed therein, a plurality of spaced apart from each other abrasive tabs mounted in the circumferential recess of the tapered portion of the spindle, and an abrasive sleeve mounted on the spindle with the tapered portion of the spindle and its plurality of abrasive tabs normally engaging and holding the abrasive sleeve on the spindle.

5. A sander tool of the class described comprising a shaft, a spindle fixedly mounted on the shaft, a circumferentially outwardly tapered portion with respect to the axis of the spindle formed on one end of the spindle having a circumferential recess formed therein, abrasive means mounted in the circumferential recess of the tapered portion of the spindle and an abrasive sleeve mounted on the spindle with the tapered portion of the spindle and its abrasive means normally engaging and holding the abrasive sleeve on the spindle.

6. A sander tool of the class described comprising a shaft, a spindle fixedly mounted on the shaft, an enlarged portion formed on one end of the spindle, abrasive means mounted on the enlarged portion of the spindle and an abrasive sleeve mounted on the spindle with the enlarged portion of the spindle and its abrasive means normally engaging and holding the abrasive sleeve on the spindle.

7. A sander tool of the class described comprising a shaft, a substantially cylindrically shaped spindle fixedly mounted on the shaft, a circumferentially outwardly tapered portion with respect to the axis of the spindle formed on one end of the spindle, abrasive means mounted on the tapered portion of the spindle and an abrasive sleeve mounted on the spindle with the tapered portion of the spindle and its abrasive means normally engaging and holding the abrasive sleeve on the spindle.
